UNITED STATES PATENT OFFICE.

MARSHALL J. ROBERSON, OF SPRING DALE, WEST VIRGINIA.

DESIGN FOR A POISON-BOTTLE INDICATOR.

52,965.

Specification for Design.

Patented Feb. 4, 1919.

Application filed September 19, 1918. Serial No. 254,872. Term of patent 3½ years.

To all whom it may concern:

Be it known that I, MARSHALL J. ROBERSON, a citizen of the United States, residing at Spring Dale, county of Fayette, and State of West Virginia, have invented a new, original, and ornamental Design for a Poison-Bottle Indicator, of which the following is a specification, reference being had to the accompanying drawing, in which—

Figure 1 is a front elevation of the poison bottle indicator.

Fig. 2 is a side elevation of the same.

Copies of this patent may be obtained for five cents each, by addressing the "Commissioner of Patents, Washington, D. C."

I claim:—

The ornamental design for a poison bottle indicator, as shown.

MARSHALL J. ^{his} ROBERSON.
